United States Patent Office

Des. 187,636
Patented Apr. 12, 1960

187,636

TOWEL HOLDER

Robert F. Nagel, Sunset Hills, Mo., assignor to John W. Wolfner, Creve Coeur, Mo.

Application May 18, 1959, Serial No. 55,956

Term of patent 7 years

(Cl. D4—3)

FIG. 1.

FIG. 2.

FIG. 3.

FIG. 4.

FIG. 5.

Fig. 1 is a top plan view of a towel holder embodying my new design;

Fig. 2 is a side elevational view thereof, the opposite side being a mirror image of the side shown;

Fig. 3 is a bottom plan view thereof;

Fig. 4 is an end elevational view thereof, the opposite end being a mirror image of the end shown; and

Fig. 5 is a sectional view taken along line 5—5 of Fig. 1.

I claim:

The ornamental design for a towel holder, substantially as shown and described.
